US0D1031357S

(12) **United States Design Patent** (10) Patent No.: **US D1,031,357 S**
(45) Date of Patent: ** Jun. 18, 2024

(54) **APPARATUS FOR MELTING COCOA BUTTER**

(71) Applicant: **TOURNESOL**, Besançon (FR)

(72) Inventors: **Sébastien Perrot**, Besançon (FR);
Ludovic Kwiatkowski, Besançon (FR);
Benoit Studle, Besançon (FR);
Guillaume Le Moigne, Tarcenay (FR)

(**) Term: **15 Years**

(21) Appl. No.: **35/513,298**

(22) Filed: **Dec. 16, 2021**

(80) **Hague Agreement Data**

Int. Filing Date: **Dec. 16, 2021**

Int. Reg. No.: **DM/218008**

Int. Reg. Date: **Dec. 16, 2021**

Int. Reg. Pub. Date: **Dec. 31, 2021**

Primary Examiner — Ricky Pham

(57) **CLAIM**

The ornamental design for apparatus for melting cocoa butter, as shown and described.

DESCRIPTION

1. Apparatus for melting cocoa butter

1.1 : Perspective

1.2 : Front

1.3 : Back

1.4 : Right

1.5 : Left

1.6 : Perspective-open apparatus

1.7 : Bottom

1.8 : Top

1.9 : Front-open apparatus

1.10 : Back-open apparatus

1.11 : Right-open apparatus

1.12 : Left-open apparatus

1.13 : Top-open apparatus

The broken lines in the drawings indicate portions of the apparatus for melting cocoa butter that form no part of the claimed design.

1 Claim, 13 Drawing Sheets
